H. W. PLEISTER.
DRIVE RING.
APPLICATION FILED JUNE 9, 1919.

Patented Feb. 24, 1920.

Henry W. Pleister ^{INVENTOR}
By
Alanson Johnson ^{ATTORNEY}

UNITED STATES PATENT OFFICE.

HENRY W. PLEISTER, OF WESTFIELD, NEW JERSEY, ASSIGNOR TO HENRY B. NEWHALL,
JR., EXECUTOR OF HENRY B. NEWHALL, DECEASED.

DRIVE-RING.

1,331,524.

specification of Letters Patent.

Patented Feb. 24, 1920.

Application filed June 8, 1919. Serial No. 302,864.

To all whom it may concern:

Be it known that I, HENRY W. PLEISTER, a citizen of the United States, residing at Westfield, in the county of Union and State of New Jersey, have invented certain new and useful Improvements in Drive-Rings, of which the following is a specification, taken in connection with the accompanying drawing.

10 My invention relates to drive rings and more particularly to such a drive ring which can be made out of hard wire and which will neither crack nor break at the bend between the shank and ring, nor will the shank buckle 15 or bend under the blows of a hammer.

My invention relates also to certain details of construction all of which will be more fully hereinafter described and pointed out in the claim.

20 In the accompanying drawing the same reference numerals refer to similar parts in the several figures.

Figure 1 is a side elevation of my new and improved drive ring;

25 Fig. 2 is a front elevation of my drive ring; and

Fig. 3 is a side elevation similar to Fig. 1, but showing the old form of drive ring.

Drive rings are driven into supports, the 30 same as nails are driven, and support wire or any suitable object by the aid of the ring portion. These drive rings are usually formed out of wire and bent sharply back upon themselves at an angle of 180 degrees 35 which is equivalent to flattening the wire on itself. This serves to strain the metal at the bend so that in hammering or driving the shank into any suitable support the drive ring will break or crack at the bend.

40 To more clearly describe my present invention I have shown the old form in Fig. 3, in which 101 is the shank, 102 the ring portion and 103 the sharp bend of the ring portion upon the shank 101. It is at 45

that it has been found in practice so many of the drive rings will crack or break in the hammering operation that they are a total loss and are returned to the manufacturer as such. Many also are ruined in the course 50 of manufacture.

If the drive ring is made of a wire soft enough to stand the 180 degree bend at point 103, Fig. 3, it has been found that the shank 101 will be too soft to withstand the 55 hammer blows which will be delivered at the

point 103, so that the shaft will bend or buckle and will not drive as a wire nail should drive.

Great difficulty has been encountered in manufacturing these drive rings so as to 60 obtain a successful one, and one which will withstand the use to which they are to be put. For example, it has been found that a drive ring formed of hard drawn low grade wire will break. So also will standard furniture 65 spring wire. Moreover it has been found that hard wire breaks a great many of the shaping dies when the ring portion is bent down sharply upon the shank portion, as shown in Fig. 3.

70 By my invention I have overcome all these objections and have successfully produced a commercial drive ring which has met all service conditions over a period of many months.

75 I take a wire sufficiently strong so that the shank 1, Fig. 1, can be driven into a wall or support in exactly the same manner as a wire nail is driven. Instead, however, of bending the ring portion 2 sharply down 80 upon the shank 1, I make the bend at 3 less than 180 degrees. I do this in any suitable manner preferably by arranging the dies so as not to crowd the metal at the bend 3. This leaves a small eyelet 4 and removes the excessive bending strains at the bend 3 which either crack the drive ring in the course of manufacture at this point, or place the metal under such strains and stresses that when 85 it is attempted to hammer the shank 1 like 90 a nail the metal will crack or break at the point 3.

I am able to use a hard wire, such as for example hard nail wire, and by introducing this small eyelet 4 I not only obtain a successful and commercial drive ring but, I 95 also reduce the cost of manufacture by reducing the breakage of the dies.

While I have mentioned hard nail wire, any wire which is sufficiently hard to permit 100 the shank 1 to be driven into a wall like a nail will come under my invention and any shape of eyelet which avoids bending the metal 180 degrees.

Having thus described this invention in 105 connection with an illustrative embodiment thereof, to the details of which I do not desire to be limited, what is claimed as new and what is desired to secure by Letters Patent is set forth in the appended claim. 110

What I claim is:—

A new article of manufacture comprising
a drive ring having a shank portion and a
spiral ring portion bent back on the shank
portion forming an eyelet between said
members, said spiral ring being open and
wound in a plane parallel with the axis of
the shank portion and located beneath the

plane of the eyelet so as to permit ready
hammering of the drive ring without hitting 10
the open spiral ring.

HENRY W. PLEISTER.
